UNITED STATES PATENT OFFICE.

ELI S. REED, OF CHATTANOOGA, TENNESSEE, ASSIGNOR TO THE UNIVERSAL SEWING MACHINE MOTOR ATTACHMENT COMPANY, OF SAME PLACE.

SPRING-MOTOR.

SPECIFICATION forming part of Letters Patent No. 444,908, dated January 20, 1891.

Application filed July 24, 1890. Serial No. 359,802. (No model.)

To all whom it may concern:

Be it known that I, ELI S. REED, a citizen of the United States, residing at Chattanooga, in the county of Hamilton and State of Tennessee, have invented certain new and useful Improvements in Spring-Motors; and I do hereby declare the following to be a full, clear, and exact description of the invention, such as will enable others skilled in the art to 5 to which it appertains to make and use the same.

This invention relates to an improvement in spring-motors adapted especially for the purpose of driving sewing-machines, but also 15 useful for actuating other kinds of machinery.

The object of the invention is to provide a simple, cheap, light, and efficient spring-motor which will consist of as few parts as possible, may be easily wound up with the expenditure 20 of a trifling amount of power, may be readily and speedily applied to any kind of a sewing or other machine, may be quickly stopped or started, and which will conform in the highest possible degree to the multitude of requirements exacted of a motor of this kind.

One principal object of the invention is to diminish the friction to the lowest minimum.

The invention therefore consists, essentially, in the construction, arrangement, and 30 combination of parts, substantially as will be hereinafter described and claimed.

In the accompanying drawings, illustrating my invention, Figure 1 is a side elevation of my improved spring-motor. Fig. 2 is a bottom 35 plan view of the same. Fig. 3 is a vertical longitudinal section of the motor. Fig. 4 is a detail plan view of the bottom part of the frame removed from the parts with which it connects. Fig. 5 is a top plan view of the 40 horizontal bevel-gear which forms part of the winding devices. Fig. 6 is a vertical section of the winding friction-wheel and its integral tube, together with the sleeve which surrounds the latter. Fig. 7 is a bottom end 45 view of the same. Fig. 8 is an end elevation of my improved spring-motor in partial section, showing the handle in its reversed position or the position which it may occupy when not needed for use. Fig. 9 is a detail view 50 of a part of the brake mechanism. Fig. 10

is a detail plan of the perforated cover-plate which is used in connection with the winding-handle to keep the clutch mechanism within said handle in proper position. Fig. 11 is a detail plan view of the end portion of 55 the winding-handle, the cover-plate shown in Fig. 10 being removed and the clutch mechanism being exposed to view. Fig. 12 is a sectional side elevation of my improved spring-motor similar to Fig. 1, and showing certain 60 of the driving-wheels reversed in position, so that the driven machine may be operated in a reverse direction.

Similar letters of reference designate corresponding parts throughout all the different 65 figures of the drawings.

A denotes the horizontal table of a sewing or other machine with which it is desired to use the motor. This may be any kind of a table belonging to any kind of a machine. 70 My purpose is to locate my motor directly beneath the table, securing it thereto, so that it may be out of the way and may occupy as small a space as possible.

The frame of my improved spring-motor is 75 secured to the under side of the machine-table A, and consists, preferably, of the following parts arranged in the following manner, so that the several mechanical parts constituting the motor may be conveniently arranged in connection therewith, and so that all the needed adjustments for perfecting the operation of the motor may be easily and readily accomplished. At the left-hand end of this frame are the parallel vertical bars B 80 (see Fig. 1,) placed a suitable distance apart and provided at their upper ends with slotted flanges, (see Fig. 2,) through which pass securing-screws or other devices, by means of which said upright bars are firmly connected 85 to the under surface of the machine-table. The slots in the said flanges permit a slight lateral adjustment of these uprights, which can be easily accomplished at any time by loosening the attaching-screws, adjusting the 90 bars, and then tightening the screws again. Connected to the lower ends of these uprights or made integral therewith is a transverse horizontal bottom bar B'. (See Figs. 2 and 3.)

C C denote another pair of parallel up- 100

rights similar to the uprights B B, at a suitable distance from said uprights B B, near the middle of the motor-frame, and similarly connected at their upper ends by means of 5 screws or other suitable attaching devices, as shown, to the under surface of the machine-table A. The lower ends of the uprights C C are connected together by means of the transverse horizontal bottom bar C⁴, which bar is 10 made integral with the longitudinal horizontal bottom bar or plate C³. The end of the longitudinal part C³ nearest to the transverse bar B' is designated by the reference-letter c and is formed suitably to permit it 15 to pass between parallel lugs or flanges formed on the under side of said bar B'. The end c is also provided with a couple of slots, through which pass screws that enter the under side 20 of bar B'. (See Figs. 2 and 4.) Thus the end c is adjustable endwise beneath the bar B', and in consequence the longitudinal part C³ and its integral transverse part C⁴ are adjustable. The end c is further provided with 25 a nut or internally-screw-threaded box made integral with the under side thereof and receiving one end of a set-screw q, the other end of which passes through a perforation in the flange on the edge of the bar B'. By adjusting this screw it will be obvious that the 30 parts C³ and C⁴ may be adjusted so as to have their position relative to the bar B' and uprights B B, as well as to the other adjacent parts, sufficiently changed to enable 35 all the mechanical devices to operate in perfect union for the accomplishment of the best possible results in the practical use of the motor.

At the left-hand end of the frame is a skeleton upright D, which is parallel to the uprights B and C, and which is secured at its 40 upper end to the under surface of the machine-table. The lower end of said skeleton upright D is provided with a bevel-tongue, which is adapted to dovetail between the beveled flanges c² c², formed on the upper side of the longitudinal bar C³ at the end thereof opposite the end c. The lower dovetailed tongue is connected to the bar C³ by means of a suitable connecting-screw. (See Fig. 3.) Furthermore, 45 the motor-frame comprises a lower or bottom skeleton frame E, (shown in section in Figs. 3 and 8 and in plan in Fig. 2,) said frame E having one part parallel beneath the longitudinal bar C³ and another right-angled integral part parallel beneath one side of the transverse part C⁴, as shown in the plan in Fig. 2. Said skeleton bottom frame E is securely connected to the lugs c' c' on the under side of the bar C³ and a lug on the under 50 side of the bar C⁴ by suitable attaching-screws, and the main purpose of this skeleton part is to permit the arrangement therein and therewith of the devices by means of which the spring is wound. Thus it will be seen that 55 the frame taken all together is a skeleton construction, consisting of the fewest possible parts, and therefore being as light as is con-

sistent with sufficient strength to support the mechanical devices. The other parts of the motor-frame are the horizontal transverse bars B², C', and C². The transverse horizontal bar B² connects the uprights B B and is located a short distance below the upper ends of these uprights. The transverse bar C' connects the uprights C C and is located a 70 short distance below the upper ends of these uprights. The transverse bar C² connects the uprights C C and is fixed at about midway of their height. These several transverse pieces may be connected in any manner that may seem best. A convenient way of locating the cross-bar C² in place is to form lugs on the inner sides of the uprights C C and allow the cross-bar C² to rest at its ends thereon, said ends being likewise enlarged to 80 permit attaching-screws which pass through the uprights C C to enter them and firmly secure the cross-bar in place.

F denotes a drum of suitable width and diameter having a cover F', which is preferably a skeleton cover and which is secured to the upper edge of the drum, as shown. The under side of the drum is formed with a central boss or enlargement, which is seated upon the bottom bar C³. Said under part of 90 the drum is preferably made in skeleton form, as shown in Fig. 2, consisting simply of the radial arms a a, which arms are preferably provided on their upper sides within the drum with ribs, as indicated in Fig. 3, upon which 95 rests the spring G, the ribs serving to diminish the friction when the spring is being wound or is unwinding.

Passing centrally through the drum F and likewise through the bottom bar C³ of the 105 motor-frame is a tube or shaft H, which may be either hollow or solid and which is formed integral with a friction-wheel H' on the lower end of the part H, beneath the bar C³, as shown in Fig. 3, the said friction-wheel and its integral shaft or tube being shown in detail in Fig. 6. The upper end of the tube H has a bearing in a circular recess formed in the under side of the transverse bar C². (See Fig. 3.)

Surrounding the tube H within the drum F is a sleeve or thimble G' which is keyed to the said tube H, so as to rotate therewith. The key g (shown in Fig. 6) is used to effect this connection. Furthermore, it will be seen 120 that the spring G is located within the drum F and is coiled around the sleeve G', one end of the spring being connected to the wall of the drum, as shown, while the other end is connected to the sleeve G' by means of a 125 screw or other attaching device g'. This spring G drives the mechanism of my machine. It may be of greater or less size and power. Obviously the rotation of the friction-wheel H' and its integral tube H in one 130 direction will revolve the connected sleeve G' and thus cause the connected spring G to wind up and become closely coiled, so that when it unwinds it will serve to actuate the gearing,

the drum F during the unwinding of the spring revolving upon the tube H, which serves as a journal therefor.

- The drum F is provided with a friction-
5 gear or friction-wheel I. This may be of equal or less diameter than the drum, in the example shown in the drawings the friction-wheel I being of less diameter than the drum and is located above the latter, being
10 mounted upon the skeleton cover of the drum and securely connected thereto. This friction-wheel I may be differently arranged with relation to the drum to which it is connected. Experience will dictate how it may be best
15 affixed thereto, and I reserve the liberty of adopting the best form thereof which may be suggested in practice. This friction-wheel I is preferably provided with a grooved perimeter or periphery.
20 The drum or barrel F connects with the driven machine through a novel system of gearing, which I will now proceed to describe. Parallel to the tube H is a vertical shaft J, having a bearing at its upper and lower ends
25 in the cross-bar B² and the bottom bar B', respectively. The upper and lower ends *j* of this shaft are preferably pointed, so that the friction thereof within the bearings may be diminished. The bearing in the bar B', is
30 simply a seat formed therein, having an annular recess around the shaft J, adapted to receive the oil or other lubricant and keep the action thereof constant upon the bearing. The bearing of the upper end of the shaft is
35 a screw-threaded plug b', which screws into an internally-screw-threaded opening in the cross-bar B². This plug b' may therefore be adjusted up or down, so as to regulate the position thereof and take up for wear. It is
40 provided with the central vertical passage, at the upper end of which is formed a cup, said passage being adapted to convey the oil or other lubricant to the upper shaft-bearing *j*, while the cup receives the lubricant and delivers it to the passage. This is shown in
45 Fig. 3. The shaft J at about midway thereof is preferably formed with an enlargement or collar J². Beneath this is a screw-threaded section J'. On this screw-threaded section is
50 a friction-wheel b, being a thin horizontal wheel made of some suitable material. This wheel b may be adjusted up or down upon the screw-threaded portion. Beneath it is a nut j², so that after the wheel has been adjusted up closely against the collar J² the nut j² may be screwed firmly into place against the under side of the wheel, and the wheel thus securely and rigidly connected to the shaft at the proper point. The periphery of
60 this friction-wheel b is in close contact with the periphery of the friction-wheel I, belonging to the drum F, and it enters the groove in the periphery of the wheel I, thus increasing the tractive force. Likewise on the vertical shaft above collar J² is a friction-wheel
65 K, preferably having a considerably larger diameter than the friction-pinion b, the hub

of said friction-wheel K having a set-screw whereby it is firmly connected to the shaft J, and the periphery of said wheel K being 70 grooved.

Parallel to the shaft J and directly in line above the tube H is another short vertical shaft L, having bearings at its upper and lower ends in the transverse bar C' and the 75 transverse bar C², respectively, said upper and lower ends of the shaft L being pointed at *l*. The bearing for the lower end *l* of the shaft L is simply a proper recess in the cross-bar C², permitting space enough to contain a 80 lubricant around the shaft, which may act at all times upon this bearing, so as to keep the action free and easy. The bearing for the upper end of the shaft L is formed in a plug l', similar to the plug b', said plug l' being 85 screw-threaded and situated within a screw-threaded opening in the transverse bar C'. On this shaft L is a friction-pinion d, and also a bevel friction-wheel M, having a hub M', provided with a set-screw e, whereby it is rigidly connected to the shaft L. The friction-wheel M has a flat rim and is beveled horizontally, so that it serves as a beveled friction-wheel, being of a diameter substantially equal to the friction-wheel K. The friction-pinion 90 d engages with the grooved peripheral surface of the wheel K. The shaft L is screw-threaded for a certain portion of its length at and below where the friction-gear d is located at L', and a nut L² travels on this screw-threaded part and binds the friction-pinion d closely between it and the hub M' of the beveled friction-wheel.

In the right-hand skeleton part D of the motor-frame is journaled a horizontal shaft 105 f, having suitable bearings in said frame. That portion of this shaft outside of the frame D is preferably screw-threaded, and on this screw-threaded portion is a bevel friction-pinion N, on one side of which is a nut 110 n and on the other side a nut n', the said bevel friction-pinion being adjustable within certain limits. This friction-pinion is in contact with the bevel friction-wheel M. (See Fig. 3.) Likewise on the shaft f within the 115 skeleton frame D is a peripherally-grooved pulley k, around which passes a belt or band m', which runs over the wheel m on the sewing-machine shaft, all as clearly shown in Fig. 1. Thus it will be seen that the belt m' 120 serves to carry power from the peripherally-grooved pulley k to the shaft of the driven machine whatsoever that machine may be.

Referring to Fig. 3, it will be seen that the bevel friction-pinion N is beneath the bevel friction-wheel M. This drives the pulley k in one direction, as shown by the arrow alongside of said pulley, and thus rotates the shaft of the driven machine in one certain direction, imparting thereby to the driven machine 125 a corresponding actuation and work. The beveled friction-wheel M, however, is reversible, so that it may be applied to the pinion N either above or below, thus rotating the latter

either in one direction or the other, as may be desired.

In Fig. 12 the wheel M is shown as applied to the pinion N, below the latter. This reversal of parts is easily accomplished by simply removing the plug-bearing l' and then reversing the shaft L, which carries with it the connected wheel M and pinion d, placing them in the position shown in Fig. 12, where the pinion d engages the periphery of the grooved friction-wheel K, just as it does in Fig. 3, and the beveled friction-wheel M has its beveled friction-surface beneath the beveled pinion N, acting upon the latter just as it does in Fig. 3, only in a reverse direction, and causing a reverse motion of the pinion N, and consequently a reverse rotation of the pulley k, which now revolves in the direction shown by the arrow in Fig. 12, and consequently imparts to the driven machine a change in its direction of movement.

Below the frictional wheel H' is a bevel gear or pinion O, having on its upper side or face (see Fig. 5) a flange or lug o and a short rounded stem, the stem and flange being integral with each other and with the gear, and on its lower side a short pointed shaft or projection o'. The flange o and integral stem are adapted to enter a recess h, formed in the face of the friction-wheel H', while the stem referred to projects a short distance into the tube H, as shown in Fig. 3. In this way the gear O is loosely connected to the friction-wheel, so that it will rotate therewith, but can be easily disconnected therefrom when desired. It will be noted that it supports the said wheel H' and its tube, keeping the upper end of the latter within its bearing in the cross-bar C². The downward shaft or pointed projection o' has a suitable bearing formed in the part of the skeleton frame E directly beneath the gear O. Thus the gear is free to turn, and in its turnings it rotates the friction-wheel H'.

By referring to Figs. 3 and 4 it will be seen that on opposite sides of the wheel H' are dogs P P, seated loosely in sockets formed in the longitudinal bar C³ of the motor-frame, said dogs having curved faces which come in contact with the periphery of the wheel H', and said dogs being provided each with a spring p, the tendency of which is to press the dogs against the wheel. Here, then, is a sort of clutch device. As the wheel H' revolves in one direction it will push the dogs out of its way, thereby compressing the springs p p; but these dogs P P quickly clutch the said wheel H' and prevent any reverse movement thereof. Thus the wheel H' and connected tube H may be rotated forward a sufficient number of times to wind the spring G tightly and coil it closely together, and the dogs P P will serve to hold the collar H', and consequently the spring, in the position in which the latter may thus be placed. The diameter of the tube or shaft H relatively to the friction-wheel H' may vary. I am not, therefore,

restricted to the particular size of this part, as shown in the drawings, but reserve the liberty of making the collar of any size and diameter relatively to the tube or shaft with which it is formed integral.

In order to rotate the gear O and thus wind the spring G, I provide certain winding devices consisting of the following parts: R denotes a horizontal shaft journaled in suitable bearings in the skeleton frame E, the inner end of said shaft R being preferably pointed and having its bearing, as shown in Fig. 8, closely adjacent to the bearing of the downwardly-projecting pointed shaft o', which belongs to the gear O, so that an oil-hole, as shown in Fig. 8, may communicate from one bearing to the other, and thus the lubricant which is fed in around the bearing for the shaft o' will leak through into the other bearing and oil the latter sufficiently to permit easy movement of the shaft R. Secured upon this shaft R is a beveled pinion R', which intermeshes with the pinion O, said pinion R' being vertically placed. Likewise on the shaft R are two collars r r, provided with set-screws, so that they may be adjustable upon the shaft, one of said collars being screwed up tightly against the pinion R', while the other is screwed tight up against the outer bearing of the shaft R. Q denotes a winding-lever having at the outer end thereof a suitably-formed handle attached at right angles, as usual, and easy to be grasped for the purpose of vibrating the said lever. The end of this lever is formed with a circular opening (see Fig. 1) wherein is placed a friction-wheel Q', which has a central square opening of suitable size to fit neatly over the square end of the shaft R. The wheel or disk Q' is held within the recess which it occupies in the end of the lever Q (covering, as it does, the circular opening in said end) by means of the plate Q³, which is perforated with an opening less in diameter than the diameter of the disk Q', said plate Q³ being fastened to the face of the lever Q by screws or other means, it being shown in detail plan in Fig. 10. Within the end of the lever adjacent to the periphery of the disk Q' is a dog Q², having a curved end in contact with the periphery of the disk Q', said mechanism thus operating and acting as a clutch, for while the lever vibrates in one direction the dog Q² will slip loosely over the periphery of the disk, the latter remaining stationary; but when the lever Q vibrates in the opposite direction, as shown by the arrow in Fig. 11, the dog will clutch the disk, thereby causing the same to rotate, and in consequence causing the rotation of the shaft R, the gearing at the end thereof, the friction-wheel and its integral tube on which the drum revolves, and thereby effecting a partial winding of the spring. A few vibrations of the winding-lever Q will therefore wind the spring up to its highest tension. It will be observed that the winding-lever Q may vibrate in either

direction, and that if it is placed upon the shaft R in the position shown in Fig. 1 the result of vibrating it in the direction shown by the arrow in this figure will be to wind 5 up the spring, whereas if it be placed upon the shaft R in the position shown in Fig. 8 it may be vibrated in the reverse direction with the effect of winding the spring. Furthermore, it will be observed that it can be 10 easily detached from or attached to the shaft R. After the spring has been wound, the handle being in the position shown in Fig. 1, it can easily be removed and the lever placed upon the shaft as it is shown in Fig. 8, whereby 15 it is out of the way and the right-angled handle at the end thereof projects inwardly instead of outwardly, and the parts are more compactly arranged and less in the way of the operator in running the machine.

20 In order that the motor may be started at any moment with promptitude or may have its motion quickly and speedily arrested at any time, and, in fact, governed and controlled at all times, with little effort on the part of 25 the operator, it becomes necessary to provide an efficient brake device. I will therefore at this point explain the form of the brake herein employed, although other forms may of course be used with other forms of the 30 motor. I preferably apply this brake to the pulley k, which, as is seen, carries the band or belt m', which communicates motive power to the driven machine.

Fig. 9 illustrates clearly a certain part of 35 the brake mechanism, and Fig. 1 shows the balance thereof, while Fig. 2 indicates in bottom plan the arrangement of certain of the parts. S designates a horizontal lever, which is fulcrumed below the machine-table at s². 40 Said lever S carries the brake-shoe S', which enters the grooved periphery of the pulley k. The shoe end of the brake-lever is provided, furthermore, with a projection s, which carries a spring s', which bears against the frame 45 and presses downward upon the brake-shoe, holding the latter tightly against the grooved periphery of wheel k. Near the other end of the brake-lever S and at right angles thereto is a right-angled or bell-crank lever T, fulcrumed 50 at its vertex on the pin t, one arm of which lever bears upon the end of the lever S, preferably entering a slot or notch s³ cut in said lever near the end thereof. To the end of the other arm of lever T is connected a rod 55 or cord v', (shown clearly in Fig. 1,) which preferably runs to the other side of the motor and is attached to one end of the lever V, fulcrumed at v on some suitable part of the motor or machine frame. Vertically below this lever 60 V is another lever U, which carries a foot or knee pad u', said lever U being fulcrumed at u and having its upper end pressing loosely against the lower end of the lever V below the fulcrual point of the latter. It will be obvious 65 that by pressing upon the pad or plate u' and pushing it in the direction shown by the arrow in Fig. 1 the result will be to shift

lever U, which will interact with the lever V, shifting it, as shown by the arrow, and moving its upper end in the direction shown by 70 the arrow, and thus pulling the cord or rod v' sufficiently to shift the bell-crank lever T, and thus depress the outer end of the lever S, whereby the brake-shoe S' will be removed from the pulley k and the spring s' temporarily contracted. When the pressure upon the lever U is released, the tension of the spring s' will serve to restore the brake-shoe to its position in contact with the periphery of the wheel k.

80 The operation of my improved spring-motor will be evident from the foregoing description of the construction and arrangement of the several parts. A few vibrations of the winding-lever will be sufficient to quickly and 85 surely coil the spring to its highest tension. This winding operation may take place at any time whether the motor is running or at rest. When it is desired to start the machine, the operator will simply press upon the brake 90 mechanism, so as to remove the brake-shoe from the pulley k and allow the coiled spring to actuate the train of multiplying friction-gears, so as to drive the shaft f and pulley k thereon, and thus actuate the driven machine. 95 If it be desired to drive the machine in a reverse direction, all that the operator needs to do is to reverse the position of the bevel friction-wheel M.

100 The several adjustments in the different parts of the frame and for the different wheels of the motor mechanism enable the operator to keep his machine in perfect condition at all times, so that it will do the best possible work and cannot get out of order. Furthermore, 105 the provision of a train of friction-gearing constitutes one great excellence and merit in this invention. Not only is the structure cheap to build, but it operates with very great efficiency, a higher speed is attained, there is 110 no noise in the operation of the parts, and the engagement of the friction-gears forms a very easy and light-running movement. Certain 115 of these friction-wheels may be made of rubber, if desired, and this material will be found very valuable when it can be used for the purpose of making the wheels of this machine, because they will operate easily, freely, and efficiently.

120 Many changes may be made in the precise construction and relative arrangement of the several parts of my improved motor without departing from the invention, and I reserve the liberty of varying the same as experience may suggest.

125 Having thus described my invention, what I claim as new, and desire to secure by Letters Patent, is—

1. In a spring-motor, the combination, with a spring-driven train of frictional gearing, 130 which includes a drum having a frictional wheel connected thereto, and said drum containing the drive-spring, of another frictional wheel having an integral part thereof serving

as a journal for the drum, together with a short shaft carrying a wheel which is belted to the driven machine, said shaft being actuated by the aforesaid train of frictional gearing.

2. In a spring-motor, the combination, with a spring-driven train of frictional gearing, that includes a drum having a frictional wheel connected thereto, and said drum containing the drive-spring, of another friction-wheel having an integral tube on which the drum revolves as a journal, a shaft carrying a wheel belted to the driven machine and actuated by the aforesaid train of gearing, and winding devices for rotating the friction-wheel and its integral tube.

3. In a spring-motor, the combination of the drum having a frictional wheel connected thereto, the spring within the drum, the friction-wheel and its integral part on which the drum revolves, the shaft above the drum, the bevel-wheel carried thereby, the multiplying gearing connecting the friction-wheel on the drum with the said shaft of the bevel-gear, and the horizontal shaft carrying the bevel-pinion acted on by the bevel-wheel and carrying also a pulley belted to the driven machine.

4. In a spring-motor, the combination of the drum, the spring-driven train of gearing, including a friction-wheel connected to the drum, a frictional disk or wheel having an integral tube on which the drum revolves, and the friction-dogs acting on said disk.

5. In a spring-motor, the combination, with the spring-driven train of frictional gearing, which includes a friction-wheel connected to the drum containing a drive-spring, of a frictional disk having an integral part thereof serving as a journal for the drum, the dogs acting to clutch said disk, and devices for rotating the same for the purpose of winding the spring.

6. In a spring-motor, the combination, with a spring-driven train of frictional gearing, including a frictional wheel connected to the drum which contains the drive-spring, of a friction wheel or disk having an integral part serving as a journal for the drum, friction-dogs acting in connection with the periphery of said friction-wheel, a bevel-gear mounted below the wheel and loosely connected thereto, so as to rotate therewith, and winding devices for actuating said bevel-gear.

7. In a spring-motor, the combination, with a spring-driven train of frictional gearing, including a frictional wheel connected to the drum containing the drive-spring, of a frictional wheel having an integral part thereof serving as a journal for the drum, the friction-spring-provided dog acting to clutch the periphery of said frictional wheel, the horizontal shaft geared to the friction-wheel, and the winding-lever provided with clutching devices whereby the said shaft is rotated for the purpose of winding the drive-spring.

8. In a spring-motor, the combination, with the spring-driven train of frictional gearing,

of the drum containing the drive-spring, a friction wheel or disk having an integral part on which said drum revolves, the dogs acting in connection with the periphery of said friction-wheel, the bevel-gear having a projection on its upper side engaging a recess in the said friction-wheel, the horizontal shaft carrying a bevel-gear engaging the aforesaid bevel-gear, and the winding-lever containing a disk which is connected to said shaft, together with one or more dogs operating in connection with said disk to cause the parts to act as a clutch.

9. In a spring-motor, the combination, with a spring-driven train of frictional gearing and a drum containing the drive-spring, of the frictional wheel having an integral part on which the drum revolves, the dogs P P, having springs p p and acting in connection with said frictional wheel, the gear O, having a projection o on the upper side thereof, adapted to enter the recess h in the friction-wheel and the bottom shaft o' beneath the gear, the shaft R, having a gear R', engaging the gear O, and the winding-lever Q, carrying the disk Q', together with the dog Q², substantially as described.

10. In a spring-motor, the combination of the drum containing a drive-spring, the train of multiplying frictional gearing for actuating the shaft which carries the pulley belted to the driven machine, the frictional wheel or disk having an integral part on which the drum revolves as a journal, the dogs for clutching said disk, and a winding-lever provided with a clutch mechanism for operating a shaft which is connected to said frictional wheel, so that the spring may be readily wound by the vibrations of the said lever.

11. In a spring-motor, a frame for the mechanical parts, consisting, essentially, of the uprights B B, connected by transverse pieces, the uprights C C, likewise connected by transverse pieces, the bottom bar C³, having an integral transverse bar C⁴ connected to the uprights C C and having an end c adjustably connected to the bottom connection between the uprights B B, the lower skeleton frame E, connected to the bottom parts, and the skeleton upright D, adjustably connected at its lower end to one end of the bottom part C³, all substantially as described.

12. In a spring-motor, the combination of the drum having a frictional wheel connected thereto, the spring within the drum, the winding frictional wheel having an integral part on which the drum revolves, together with the clutching-dogs, the shaft above said drum carrying a large bevel friction-wheel, the multiplying gearing connecting the frictional wheel on the drum with the shaft above, and the horizontal shaft carrying a bevel-pinion engaging the bevel-wheel and likewise a pulley belted to the driven machine, together with a suitable supporting-frame for the several mechanical parts, substantially as described.

13. In a spring-motor, the combination of the drum having a frictional wheel connected

thereto, the spring within the drum, the winding frictional wheel with its integral tube, on which the drum revolves, the short shaft above the drum, the train of multiplying frictional gearing connecting the friction-wheel on the drum with the said shaft, together with the large bevel-wheel on the said shaft, said bevel-wheel being so arranged that it may be readily reversed to act in combination, either above or below, with a bevel-pinion on the horizontal shaft carrying a pulley belted to the driven machine.

14. In a spring-motor, the combination of a drum, a frictional wheel connected to said drum, a spring within the drum, the winding frictional wheel having an integral tube on which the drum revolves, a shaft parallel to said tube and carrying a friction-pinion engaging the friction-wheel on the drum and also carrying the large friction-wheel, the short vertical shaft above the drum carrying the friction-pinion engaging the aforesaid large friction-wheel and also carrying a bevel friction-wheel, and a horizontal shaft having thereon the pulley belted to the driven machine, and the beveled friction-pinion engaged by the beveled friction-wheel.

15. In a spring-motor, the combination of a drum having a frictional wheel connected thereto, a spring within the drum, a winding frictional wheel having an integral tube on which the drum revolves, a shaft above the drum carrying a bevel friction-wheel and a small friction-pinion, the latter being adjustable on the shaft and the shaft itself being reversible, a parallel shaft carrying an adjustable friction-pinion engaging the friction-wheel on the drum and also an adjustable friction-wheel engaging the friction-pinion on the short shaft, and a horizontal shaft carrying an adjustable bevel friction-pinion, together with a pulley.

16. The combination of a drum having a grooved friction-wheel, a winding frictional wheel having an integral tube on which the drum revolves, the short shaft above the drum carrying an adjustable friction-pinion and a large bevel-wheel, a parallel shaft having a screw-threaded part and carrying thereon an adjustable friction-pinion, together with a nut, a large peripherally-grooved friction-wheel likewise adjustable on said shaft, and a horizontal shaft carrying a peripherally-grooved pulley and having one end screw-threaded, whereon is carried a bevel friction-wheel adjustable between nuts, with its bevel-surface in contact with the aforesaid friction-wheel.

17. The combination of the drum having a connected friction-wheel, a spring within the drum, a winding friction wheel or disk having an integral tube on which the drum revolves, a multiplying train of friction back gearing, and the horizontal shaft carrying the pulley belted to the driven machine and actuated by said back gearing, together with the

frame supporting said mechanical parts and adjustable at different points, as described.

18. The combination of the drum F, containing spring G and having friction-wheel I, the winding-disk H', having the integral part H, on which the drum revolves, the vertical shaft J, having the screw-plug bearing b' at its upper end, the short shaft L above the drum and having the screw-plug bearing l' at its upper end, and the train of multiplying friction-gearing carried by said shaft, substantially as described.

19. The combination of a drum having a friction-wheel, a spring within the drum, a winding friction wheel or disk having an integral tube on which the drum revolves, the shaft above the drum carrying friction-gearing, the parallel shaft carrying frictional gearing, and the horizontal shaft carrying friction-gearing, all arranged substantially as described, so that the spring may actuate the train of friction-gearing for the purpose of driving a machine belted to the pulley on the horizontal shaft.

20. The combination of the drum F, having frictional wheel I, the spring G within the drum, the winding frictional wheel H', having an integral part H on which the drum revolves, the shaft J, carrying friction-pinion b, engaging wheel I, and also carrying friction-wheel K, the shaft L, carrying friction-pinion d, engaging wheel K, and also beveled friction-wheel M, and the horizontal shaft f, carrying bevel friction-pinion N and pulley k, substantially as described.

21. In a spring-motor, the combination, with the spring-driven train of friction-gearing, which includes a drum having a connected frictional gear-wheel and containing the drive-spring, of a frictional winding wheel or disk having an integral part thereof serving as a journal for the drum, a sleeve surrounding said journal within the drum and keyed thereto, one end of the spring being attached to said sleeve and the other to the drum, and the horizontal shaft carrying a pulley which is belted to the driven machine, which shaft is actuated by the aforesaid train of gearing.

22. In a spring-motor, the combination of the drum having a frictional gear-wheel connected thereto, the spring within the drum, the frictional winding disk or wheel having an integral tube on which the drum revolves, the sleeve or thimble surrounding said tube within the drum and connected to the tube, to which sleeve one end of the spring is attached, the shaft above said drum carrying the bevel friction-wheel, the horizontal shaft having a bevel-pinion actuated by said wheel, and the multiplying gearing connecting the frictional wheel of the drum with the short shaft for the purpose of actuating the latter.

23. The combination, in a spring-motor, of the drum having a frictional gear-wheel connected thereto, the spring within the drum, the frictional winding-disk having an inte-

gral tube on which the drum revolves, the horizontal shaft carrying a pulley belted to the driven machine, a sleeve on the tube within the drum, to which sleeve one end of 5 the spring is attached, the short shaft carrying its friction-gear and the parallel shaft carrying a friction-pinion that engages the friction-wheel on the drum, and a friction gear-wheel that engages a friction-pinion on the 10 short shaft.

24. The combination of the drum and its connected friction gear - wheel, the spring within the drum, the frictional winding-disk having an integral part on which the drum revolves as a journal, a sleeve surrounding 15 said journal, to which sleeve one end of the spring is connected, the horizontal drive-shaft, the frictional gearing connecting the friction-wheel on the drum with the said horizontal 20 shaft and the dogs for clutching the frictional winding - disk, the winding - lever provided with clutch mechanism, and the shaft geared to the frictional winding-disk, all designed to operate in combination substantially as de- 25 scribed.

25. The combination of the drum, the frictional gear - wheel connected thereto, the spring within the drum, the frictional winding-disk having an integral tube on which 30 the drum revolves, the horizontal shaft carrying a pulley belted to the driven machine, the train of multiplying friction-gears connecting the friction-wheel on the drum with the said pulley-shaft, the dogs acting to en- 35 gage the frictional winding-disk, the beveled gear loosely connected to said disk, the horizontal shaft having a bevel-gear engaging the aforesaid gear, the winding-lever provided with the disk Q', which is provided with the

opening to receive the end of the aforesaid 40 shaft, and a dog Q², operating in connection with the periphery of said disk, all substantially as described.

26. In a spring-motor, the combination, with the pulley belted to the driven machine, of a 45 brake-lever having a shoe applied to the periphery of said pulley, a spring acting to press said shoe against said periphery, a right-angled lever having one arm operating against the end of the brake-lever to remove the shoe 50 from the pulley, a connection between the end of the other arm with a lever fulcrumed on the machine-frame, and a second lever carrying a plate or pad and having its other end operated in connection with the lever just mentioned, substantially as described.

27. The combination, with the pulley k, of the spring-actuated brake-lever S, having a shoe S', the right-angled lever T, having one arm acting upon the end of the lever S, and 60 the levers U and V, said lever V being connected by the connection v' with the right-angled lever T.

28. The combination, with the pulley k, of the brake-lever S, fulcrumed at s², having 65 shoe S' and provided with spring s', the right-angled lever T, fulcrumed at t, the lever V, fulcrumed at v and connected by a connection v' with the end of the right-angled lever T, and the lever U, fulcrumed at u and having a knee or foot pad u', all substantially as described.

In testimony whereof I affix my signature in presence of two witnesses.

ELI S. REED.
